UNITED STATES PATENT OFFICE.

AUGUST HOLMQUIST, OF HOOPESTON, ILLINOIS, ASSIGNOR TO SPRAGUE CANNING MACHINERY COMPANY, OF CHICAGO, ILLINOIS, A CORPORATION OF ILLINOIS.

NOZZLE CLEANER.

Application filed September 27, 1920. Serial No. 413,102.

To all whom it may concern:

Be it known that I, AUGUST HOLMQUIST, a citizen of the United States, residing at Hoopeston, in the county of Vermilion and 5 State of Illinois, have invented new and useful Improvements in Nozzle Cleaners, of which the following is a full, clear, concise, and exact description, reference being had to the accompanying drawing, forming a 10 part of this specification.

My invention relates to filling machines, and more particularly to an attachment for filling machines, for scraping off the discharge means to prevent the material from 15 dripping, and thus getting where it is not wanted.

One of the objects of my invention is to provide an improved filling machine, in which means are provided for automatically 20 cleaning the discharge means to prevent dripping.

Further objects will appear from the detailed description to follow and from the appended claims.

25 In the drawings in which an embodiment of my invention is shown—

Fig. 1 is a vertical axial section of a filling machine substantially on the line 1—1 of Fig. 2;

30 Fig. 2 is a sectional plan view of the filling machine shown in Fig. 1;

Fig. 3 is a side elevation showing the nozzle cleaning device; and

35 Fig. 4 is a section on the line 4—4 of Fig. 3.

The filling machine shown in the drawing is of an old type, and no novelty is claimed in the construction of a filling machine per se, the novelty residing in the 40 device for cleaning off the discharge mechanism, and in its combination with the filling machine.

In filling machines for handling sticky or 45 slow flowing materials, such as syrup, marshmallow filling and the like, it has been found that the material will stick to the discharge means and will drip and thus cause the material to get where it is not wanted.

50 The filling machine shown in the drawing comprises in a general way, a rotary reservoir 10 for the material to be filled, a stationary cut-off plate 11 in the bottom of the reservoir 10, a circular series of measuring cylinders 12 and plungers 13 located

underneath the reservoir 10 and rotatable therewith, a circular series of can sweeps 14, secured to and rotatable with the measuring cylinders 12, and a circular series of discharge nozzles 15 and plunger valves 16 for controlling the discharge from the measuring cylinders 12. Suitable cam means are provided for controlling the movement of the pistons 15 which operate in the measuring chambers 12, and a suitable cam-track 17 is provided for controlling the movement of the plunger valves 16, the plunger valves 16 being provided with followers 18 for engaging the circular cam-track 17. A suitable frame 19 is provided 60 for supporting the various parts in their proper relation.

In order to facilitate an understanding of the cleaning or scraping attachment for the discharge means, a brief description of the 75 operation of the filling machine proper will now be given. The material, such as syrup or the like to be filled, is placed in the rotary reservoir 10, and the machine is put in operation to cause this reservoir 10 to 80 rotate together with the measuring cylinders 12 and pistons 13, and the discharge nozzles 15 and plunger valves 16. The cut-off plate 11, however, remains stationary, being supported by a stationary sleeve 20 85 which surrounds the rotary shaft 21, to which the rotary parts are secured. Cans are fed to the machine in front of the sweeps 14, and discharged by any suitable means not necessary to be shown or to be 90 described in detail. As the parts revolve the pistons 13 are caused to reciprocate in the measuring cylinders 12, and the plunger valves 16 also are caused to reciprocate in the discharge nozzles 15, the reciprocation 95 of the pistons 13 and plunger valves 16 being suitably timed to cause charges of the material to be drawn down into the measuring chambers 12 while the plunger valves 16 are in closing position, and while the 100 measuring chambers are moving underneath the opening 22 in the stationary cut-off plate 11, as shown at the right of Fig. 1, and also being timed so that the plungers 13 will operate to discharge the material from the 105 measuring chambers 12 at a time when these measuring chambers are underneath the unapertured portion of the cut-off plate 11, and while the plunger valves 16 are in open position as shown at the left in Fig. 1.

In using this machine with sticky or slow flowing substances, it is readily seen that the material would tend to stick to the discharge nozzles 15 and drip as the nozzles move 5 along, and drip at a time when there would be no receptacle underneath the discharge nozzles, so that the material would drip on the machine and cause it to become gummed up. To remedy this, I provide an attachment 10 to automatically scrape off the discharge nozzles 15, as these nozzles rotate. This device comprises a circular rotary knife 23, provided on its upper surface with a star-wheel 24, the arms of which are located in 15 position to be engaged by the discharge end of the nozzles 15 as they rotate, the knife itself being located so that it will snugly engage the under face of the discharge nozzle 15 to scrape off any material which may be 20 sticking to this discharge nozzle, and to cause this material thus cut off to be deposited in the receptacle which is traveling underneath.

In order to prevent any material from sticking to the rotary knife itself, I provide 25 a roller 25, which engages the under surface of the rotary knife 23 and operates in a bath 26 of oil or other suitable material, causing a film or layer of oil to be applied to the under surface of the knife 23 to prevent the 30 sticky material from sticking to the under surface of this knife. In certain substances, such as the filling for marshmallows, it may be desired to have the roller 25 operate in a bath of powdered sugar or the like, instead 35 of a bath of oil, this causing a film or layer of powdered material to adhere to the lower face of the roller knife 23 to prevent the material from sticking to the knife.

The rotary knife 23 may be secured to a 40 vertical shaft 27 mounted in a bearing 28 in a bracket 29. The roller 25 may be mounted on a shaft 30 secured to a bracket arm 31 extending from the bearing 28.

In operation, as the rotary series of nozzles 15 successively engage the arms of the star-wheel 24, the engaging nozzles causes 45 the star-wheel to rotate through an angle of 90 degrees to bring the succeeding arm in position to be engaged by the succeeding nozzle 15. This rotation of the star-wheel 24 causes a rotation of the knife 23, which engages the under face of the discharge nozzle 15 with a rotary drawing motion to cut off the surplus material which may be sticking to the bottom of the nozzle, and to cause 50 this surplus material to drop down into the

receptacle underneath, the under surface of the knife 23, as previously described being provided with a film or coating which will prevent adherence of the sticky material to 60 the under surface of the knife.

Having thus described my invention, what I claim as new and desire to secure by Letters Patent of the United States is:

1. An automatic filling machine provided 65 with a series of discharge means movable consecutively in a definite path, means for causing material to be discharged by means of said discharge means, and means for removing the surplus material which sticks to 70 said discharge means as said discharge means move, said means for removing comprising a rotatable knife, and means for intermittently rotating said knife.

2. An automatic filling machine provided 75 with a series of discharge means movable consecutively in a definite path, means for causing material to be discharged by means of said discharge means, and means for removing the surplus material which sticks to 80 said discharge means as said discharge means move, said means for removing comprising a rotatable knife, and means for intermittently rotating said knife, said last means comprising a star-wheel actuated by 85 said discharge means.

3. An automatic filling machine provided 90 with a series of discharge means movable consecutively in a definite path, means for causing material to be discharged by means of said discharge means, and means for removing the surplus material which sticks to 95 said discharge means as said discharge means move, said means for removing comprising a rotatable knife, and means for applying a coating to prevent the material adhering to the knife.

4. An automatic filling machine provided 100 with a series of discharge means movable consecutively in a definite path, means for causing material to be discharged by means of said discharge means, and means for removing the surplus material which sticks to 105 said discharge means as said discharge means move, said means for removing comprising a rotatable knife, and means for applying a coating to prevent the material adhering to the knife, said preventing means comprising a roller engaging the face of the knife.

In witness whereof, I have hereunto subscribed my name.

AUGUST HOLMQUIST.
